UNITED STATES PATENT OFFICE.

HENRY VICK, OF EVANSTON, ILLINOIS.

CIRCULATOR FOR BOILERS.

Application filed August 30, 1926. Serial No. 132,464.

The invention relates to water circulators and primarily to devices of this character which are designed to promote circulation of water between the tubes of a boiler and thereby facilitate the heating of the water.

The invention has as its prime object the provision of a circulator which may be incorporated in and removed from the boiler by inserting the circulator through an opening such as the manhole of the boiler to permit the circulator to be arranged between the vertical rows of tubes of the boiler and provide walls between which the water may circulate and thereby promote and facilitate the heating of the water in the boiler.

It is a further object to provide a construction, the elements of which may be connected together either prior or subsequent to their introduction into the boiler and their arrangement between the tubes of the boiler.

It is another object to form the elements of the circulator so that when associated with each other an open ended tube is produced, one of which may be arranged adjacent another within the boiler between the tubes throughout the length of the boiler.

The invention will be explained and more readily understood when read in conjunction with the accompanying drawings which show various structures whereby the invention may be accomplished, it being therefore obvious that changes and modifications may be resorted to without departing from the spirit of the invention as expressed in the appended claims forming a part hereof.

In the drawings:

Fig. 1 is a central vertical section of a tubular boiler showing my improved water circulators associated therewith.

Fig. 2 is a horizontal sectional view of a portion of a boiler showing the circulators in side elevation.

Fig. 3 is a detail perspective view of one form of circulator contemplated by the invention and

Fig. 4 is a perspective view of another form of circulator which may be employed.

The embodiment of the invention illustrated in Fig. 3 contemplates the provision of an open ended substantially rectangular element 10 which is designed to be inserted through the manhole 11 of the boiler 12 and be arranged between vertically arranged rows of tubes 13. Each of these elements 10 is of a dimension which permits of its being passed through the manhole 11, and to be located be-

tween said tubes as above explained and is of a length sufficient to extend from the upper to the lower tubes 13 between which said element is located to thus provide a passage 60 which is transverse to the tubes through which the water may circulate. It is of course understood that a number of these elements 10 are employed one being arranged adjacent another between said tubes. To 65 accomplish this feature each element as it is passed through the manhole and located between the tubes is subsequently moved toward an end of the boiler to thereby provide a number of said elements 10 preferably in 70 contacting relation with each other throughout the length of the boiler. Each of these elements 10 is provided with a means such as 14 whereby to engage the uppermost tubes and support said elements between the tubes 75 and is further provided with a member 15 which after the elements 10 are located between the tubes is attached to each of said elements and caused to engage the underside of the uppermost tube to cooperate with the 80 means 14 to hold each element 10 in its proper position with relation to the tubes. From the foregoing description it is manifest that a means is provided whereby an ordinary boiler may be provided with a means for causing 85 circulation of the water without necessitating any change being made in the boiler and furthermore that these elements may be readily removed from the interior of the boiler to cleanse or repair them should this 90 at any time be found necessary or desirable.

The structure illustrated in Fig. 4 may also be employed. This structure contemplates an arrangement which employs separable elements which when associated with each other form a device resembling that described in connection with Fig. 3 both as to form and operation, however provides a construction which may be assembled after the elements are located within the boiler, which may under some conditions be of 100 advantage. This structure contemplates the utilization of separable side and end walls respectively designated 16—17, 18 and 19. The side walls 16 and 17 of this structure are 105 each provided with an inturned part 20—20 which in the present instance are provided with a plurality of lugs 21—21 which provide one part of a holding means for securing the end members 18 and 19 with respect 110 to the side wall members 16 and 17 the latter of which are provided with apertures 22 for

the reception of the lugs 21 of the side wall members to thereby detachably connect the various walls together to produce a structure similar to that previously referred to. The side walls 16 and 17 are also provided with the holding elements 23—23 and 24 whereby the device may be supported between the tubes of the boiler.

From the foregoing description of the structure shown in Fig. 4 it is manifest that the elements of which this device consists may while in separated relation be introduced into the boiler and be connected together after their insertion therein to form a means for facilitating circulation of the water between the tubes of the boiler, which under some circumstances is of advantage, as it is manifest that conditions will arise which would prohibit the introduction of a device formed in the manner illustrated in Fig. 3. In operation the water surrounding the tubes 13 becomes heated and rises to the top of the water in the boiler and, by virtue of the relatively cool water located in the passages 10 which is at this time descending in said passages, draws the water which has liberated its steam or become cooled through said passages to the lower portion of the boiler. The water located between and contacting with the tubes of the boiler becomes heated and rises, the rising water being replaced by the relatively cool descending water in said passages, causing circulation of said water through said passages and between the tubes 13 of the boiler, which thus facilitates heating of the water and accomplishes a reduction in the cost of operation of the boiler.

From the foregoing description of the invention it is evident that a simple construction is provided whereby a boiler may be provided with a means for directing the circulation of the water between the tubes and which may be applied to the boiler without necessitating any change being made thereto and which may be applied by passing the elements forming the device through an opening such as the manhole of the boiler.

Having thus described the invention what

I claim and desire to cover by Letters Patent is:—

1. The combination with a fire tube boiler having a pair of opposed banks of tubes arranged to form a lane between them, a circulating system including a series of horizontally aligned vertically arranged conduits providing substantially contacting units forming a part of said system, each unit being composed of detachably united side and flat end walls, and means for supporting said conduits between said tubes of the boiler.

2. The combination with a fire tube boiler having a pair of opposed banks of tubes arranged to form a lane between them, a circulating system arranged in said lane, a series of horizontally aligned vertically arranged conduits composed of detachably united side and end walls, the end walls of each conduit being of a width throughout their length, which substantially corresponds to the width of the lane formed between said tubes, the end and side walls having means which co-operate with each other to allow detachable connection of said end and side walls, the end walls of the intermediate conduits being arranged in substantial contacting relation with the end walls of the respective adjacent conduits.

3. The combination with a fire tube boiler having a pair of opposed banks of tubes arranged to form a vertical, horizontally extending lane between them, a plurality of conduits located in said lane and removable therefrom by being passed endwise upwardly between the upper tubes forming said lane, said conduits being disposed in horizontal alignment with each other with the end walls of the intermediate conduits contacting the end walls of the respectively adjacent conduits to thereby provide a substantially continuous vertically arranged and horizontally extending passage in said lane which forms part of a circulating system.

In witness whereof, I hereunto subscribe my name this 23rd day of July, A. D. 1926.

HENRY VICK.
